UNITED STATES PATENT OFFICE.

BERNARD M. ABELL AND WILLIE OSTRANDER, OF NEW YORK, N. Y.

MEANS FOR ORNAMENTING SHEET-METAL ARTICLES.

SPECIFICATION forming part of Letters Patent No. 482,837, dated September 20, 1892.

Application filed April 30, 1892. Serial No. 431,324. (No model.)

To all whom it may concern:

Be it known that we, BERNARD M. ABELL and WILLIE OSTRANDER, citizens of the United States, and residents of New York, in the county of New York and State of New York, have invented certain new and useful Improvements in Means for Ornamenting Sheet-Metal Articles, of which the following is a specification.

10 The invention relates to improvements in means for ornamenting sheet-metal articles, such as bowls, pitchers, cane-handles, and the like, which articles in the larger silverware factories are usually ornamented by "snarling" and other slow and tedious forms of labor.

15 The invention consists in the devices and combinations of parts hereinafter described and claimed; and its object is to produce 20 suitable apparatus whereby under the action of hydraulic pressure the plain walls of a bowl or other article may have imparted or transferred to them the entire ornamental design engraved in the walls of the matrix 25 which will inclose and maintain said article.

In carrying our invention into practice we 30 make use of a sectional die to receive the bowl or other article to be treated, a vertically-reciprocating cylinder which enters the die and through which the plunger connected 35 with the ram of the hydraulic jack moves, and a novel press for maintaining the sections of the die under the great pressure necessary to properly effect the transfer of the 40 design from the walls of the matrix to those of the bowl or other article therein.

Our invention pertains particularly to the vertically-reciprocating cylinder above referred to, with its attendant devices, and to 45 the press sustaining the sectional die.

Referring to the accompanying drawings, forming part of this application, Figure 1 is a central vertical section through an apparatus constructed in accordance with and embodying the invention. Fig. 2 is a transverse section of same on the dotted line 2 2 of Fig. 1, looking downward. Fig. 3 is a detached perspective view of one of the followers and platens, constituting a portion of the press 50 for maintaining the die. Fig. 4 is a detached transverse section on the dotted line 4 4 of Fig. 1. Fig. 5 is an enlarged central vertical

section of the lower end of the vertically-reciprocating cylinder which enters the die. Fig. 6 is an enlarged detached central vertical section through a portion of one of the followers and the means whereby it is secured to its operating-screw, and Fig. 7 is a central vertical section of a bowl in the nature of a blank adapted for treatment in the die. 55 60

In the drawings, A designates the bed-plate of the apparatus, B the top frame thereof, and C C the vertical rods or standards connecting said bed-plate A and top frame B and having between their upper portions the transverse frame D, which supports the hydraulic jack E, of usual construction. Upon opposite sides of the lower end of the ram F of the hydraulic jack E are provided the lugs G, from which is suspended by means of the links H the 65 plunger I, having upon its lower end the customary cup-shaped packing J. The upper end of the plunger I at opposite sides is provided with the lugs K, which correspond with the lugs G and receive the lower ends of the 70 links H, and said upper end of the plunger I is broadened to offer an effective bearing-surface for the lower end of the ram F when the latter is depressed thereon. 75

It will be observed upon reference to Fig. 1 80 that the length of the links H is such that the plunger I is dropped a short distance below the lower end of the ram F, and hence upon the descent of the ram and plunger the latter will be lowered upon the liquid and the former 85 will thereafter travel downward a short distance before the full pressure of the ram is transmitted to the plunger.

The bed-plate A will be properly supported upon a base L and is provided at its center 90 with the aperture M to receive the pin N, extending centrally downward from the base-plate O of the sectional die P. The bed-plate A is also provided at its corners with the internally-threaded bearings Q for the screws 95 R, which are horizontally arranged and provided at their outer ends with suitable handles S, by which they may be operated. The screws R extend inward on direct lines toward the opposite sides of the sectional die P 100 and carry upon their inner ends the followers T and plates or platens V, the former being provided with the dovetailed grooves W to receive the correspondingly-formed ribs X

upon the outer face of the platens V. The inner extremities of the screws R are threaded to receive the collars Y, which are adapted to enter the cavities a, formed in the outer face of the followers T and to be held therein by means of the internally-threaded nuts b, screwed to said followers.

In the arrangement of the screws R, followers T, and nuts b we first pass the inner extremity of the screw R through the nut b, then apply the collar Y to the end of said screw, and thereafter insert the said collar Y into the cavity a and screw up the nut b, thereby securely retaining the whole in place. The arrangement of the screw R with the follower T is such that the parts may be separated, when desired, for repairs or for other purposes. The lower surfaces of the followers T are provided with the ribs d and rollers e, the former extending downward and being adapted to travel in the grooves f, formed in the bed-plate A, while the rollers e move upon the surface of said bed-plate and facilitate the adjustment of the screws R and followers T toward and from the sectional die P. The bed-plate a is provided with four of the screws R, and each carries the follower T and platen V. The platens V are also provided with rollers g to aid in their adjustment toward and from the sectional die P, and said platens V are adjustable laterally by means of the ribs X and grooves W for the purpose of adapting them to the size of the dies. The screws R may, if desired, be provided with locking-nuts R' of customary construction.

The die P (illustrated in the drawings) is composed of the sections h, provided with corresponding ribs i and grooves j and apertures k and pins m to aid in properly securing them together, and within the die P, whether composed of the specific sections h or of sections otherwise formed, is provided the matrix n, whose surfaces will be engraved with the design it is intended the finished article shall bear. Above the matrix n there is provided in the die the central opening t, having vertical walls and a base u, which inclines inward toward the center of the matrix n, thereby forming the inclined surfaces terminating at the edges of the opening w. The sheet-metal article to be treated in the die will conveniently fit the matrix n and have upon its upper end the flange x, which will rest upon the inclined surfaces of the base u of the central opening t.

At a suitable elevation above the sectional die P there is secured to the standards C the transverse frame A', having the central vertical opening B' and held in place by means of the brackets C' and screws D', the latter being adapted to enter any of the series of apertures F' provided in the inner faces of the standards C. The purpose of providing a series of the apertures F' is to permit the adjustment of the frame A' upward or downward, in accordance with the height of the sectional die and other circumstances. Within

the opening B' in the center of the frame A' is secured the revoluble internally-threaded sleeve G', having the hand-wheel H' and being prevented from losing its position in said opening B' by means of shoulders I', engaging the upper and lower surfaces of said frame A'. Within the internally-threaded sleeve G' is arranged the externally-threaded cylinder J', having the central chamber K', and the vertical exterior grooves L', receiving the inner ends of the arms M', which arms, in connection with said grooves, insure a direct vertical movement in the cylinder J' and prevent any revolving motion thereof. The arms M' are bolted to the lower surface of the frame A' and will be of convenient form and size to pass below the internally-threaded sleeve G' and properly engage the said grooves L', formed in the opposite sides of the cylinder J'. The lower end of the cylinder J' is reduced to form a threaded stem N' and has the annular recess O', which receives the angular packing P', and the upper portion of the nut Q', screwed home upon the said stem N'. The formation of the packing P' and nut Q' is of importance, since it is essential that the liquid within the bowl inclosed in the die P be most securely held; otherwise it will escape under the action of the hydraulic pressure.

It will be observed upon reference to Figs. 1 and 5 that the lower surfaces of the nut Q' taper downward and inward and that above said tapered surfaces the nut is provided with the annular recess S' to receive the inwardly-tapering lip T' of the packing P'. When the cylinder K' is lowered into the die P, the lower extremity thereof will enter the opening w and the nut Q' and packing P' will engage the flange x of the bowl, and when the parts are in this position the annular lip T' of the packing P' will bear against the flange x of the bowl and form a liquid-tight joint. Any water rising around the lower end of the cylinder J' and nut Q' will pass beneath the annular lip T' and more firmly press the same against the flange x, thus effectually sealing the joint and preventing all leakage. The packing P' is of angular form in vertical section, as shown, and is securely held in place by the nut Q', which is adapted to be removed and leave the packing in condition to be withdrawn when desired.

In the operation of the apparatus the bowl or other article it is desired to shape or ornament will be placed in the previously-prepared die and the latter then seated upon the bed A and there securely held by the platens V, which will be firmly backed by the screws R. The bowl and die being in position, the cylinder J' will be lowered by the rotation of the sleeve G' until its lower extremity is within the mouth of the bowl, and the nut Q' and the packing P' are solidly pressed against the flange x thereof, whereupon the liquid will be introduced to about fill the bowl

and the ram of the hydraulic jack lowered, causing the descent of the plunger I through the cylinder J' and upon the liquid in the bowl. The pressure of the hydraulic jack being continued, its force, acting through the plunger I upon the liquid, will swell the walls of the bowl into the interstices of the die, and thus the bowl at a single operation will have imparted to it the form of the matrix and whatever design, whether in intaglio or relief, the walls thereof may bear. After the bowl has thus been shaped and ornamented, the ram F and plunger I will be elevated and the cylinder J' raised by the reverse rotation of the sleeve G'. Thereafter the platens V, by the reverse rotation of the screws R, will be drawn outward, and the die thus left free will be removed, its sections separated, and the bowl withdrawn. Another bowl with plain surfaces may then be placed in the die and the latter sustained by the platens V, while the above-described operation of lowering the cylinder J' and plunger I is repeated. The dies as to form, size, and design will vary with the conditions it is desired to produce in and the nature of the article under treatment, and hence it will be understood that the platens V should be adjusted on the followers T in accordance with the size of the die. It will be observed that the platens V are equal in length and that they overlap each other at one end, thus permitting their adjustment to inclose a very small die centered on the bed-plate A. Whether the platens V are adjusted to close about either a large or a small die, the screws R will exert their pressure on direct lines centrally against the opposite sides of the die and firmly bind the same. The platens V and screws R constitute a press for holding the sections of the die with the requisite firmness for resisting the great force of the hydraulic jack and form an important feature of the invention. It will not be necessary in every instance to employ four screws R and four platens V, and hence the invention is not confined to any special number of the screws and platens; but that number thereof will be used which may be required by the varying forms of the die-sections.

What we claim as our invention, and desire to secure by Letters Patent, is—

1. The die having the matrix to receive the article to be treated, combined with the reciprocating threaded cylinder adapted at its lower end to enter the mouth of said die, the packing at the lower end of said cylinder to form a liquid-tight joint, the internally-threaded revoluble external sleeve engaging said cylinder, means for preventing vertical movement in said sleeve, the guide for preventing revolving motion in said cylinder, and means for exerting pressure upon the liquid within said article, substantially as and for the purposes set forth.

2. The die having the matrix to receive the

article to be treated, combined with the reciprocating threaded cylinder adapted at its lower end to enter the mouth of said die, the packing at the lower end of said cylinder to form a liquid-tight joint, the internally-threaded revoluble external sleeve engaging said cylinder, the vertically-adjustable frame supporting said sleeve and preventing vertical movement therein during its rotation, the guide for preventing revolving motion in said cylinder, and means for exerting pressure upon the liquid within the said article, substantially as and for the purposes set forth.

3. The die having the matrix to receive the article to be treated and the inclined mouth leading to said matrix, combined with the hollow cylinder through which hydraulic pressure is applied, the nut on the reduced lower end of said cylinder and conforming to said inclined mouth, and the annular packing held in place by said nut and having the downwardly and inwardly inclined lip to engage the inclined flange on the article to be treated, substantially as and for the purposes set forth.

4. The die having the matrix to receive the article to be treated, combined with the reciprocating threaded cylinder, the nut on the reduced lower end of said cylinder, the packing held in place by said nut and having the annular downwardly-depending lip, the revoluble sleeve engaging said cylinder, the frame supporting said sleeve, the guide for the cylinder, and the plunger adapted to enter said cylinder, substantially as and for the purposes set forth.

5. The die having the matrix to receive the article to be treated, combined with the hollow reciprocating non-revoluble cylinder having packing at its lower end and adapted to engage the article within said die, the plunger in line with and adapted to enter said cylinder, and hydraulic apparatus carrying said plunger, substantially as and for the purposes set forth.

6. The die having the matrix to receive the article to be treated, combined with the adjusting pressure-screws R, in line with the sides of said die, the laterally-adjustable platens V, carried by said screws, the hollow cylinder in line with the said matrix and having packing at its lower end to form a liquid-tight joint, and the hydraulic plunger within said cylinder, substantially as and for the purposes set forth.

7. The die to receive the article to be treated, the bed-plate, the screws in line with the sides of the die, the followers on said screws, the platens adjustable on said followers, the cylinder communicating with the interior of said article, and the plunger within said cylinder, substantially as and for the purposes set forth.

8. The die having the matrix to receive the article to be treated, the screws in line with the sides of the die, the followers on said

screws, the guides for the followers, the platens on said followers, the cylinder communicating with the interior of said article, and the plunger within said cylinder, substantially as and for the purposes set forth.

9. The die, combined with the adjusting pressure-screws R in line with the sides thereof and mounted in the threaded bearings Q, and the laterally-adjustable independent platens V, carried by the said screws

and overlapping each other at one end, substantially as and for the purposes set forth.

Signed at New York, in the county of New York and State of New York, this 27th day of April, A. D. 1892.
